CONDENSER TUBE CLEANER WITH
RESILIENT SCRAPER ELEMENTS

Cecil M. Griffin, Pittsburgh, Pa.

Application June 21, 1946, Serial No. 678,221

7 Claims. (Cl. 15—104.06)

1

This invention relates to a tool for cleaning tubes or a tube cleaner, and more particularly to a tube cleaner of the type employed to remove deposits from condenser tubes.

In cleaning condenser tubes, and especially those of small diameter, a tube cleaner of a small size must of necessity be employed, and yet it should be a cheap and simple article to manufacture, speedy and effective in its cleaning action, and, despite its small size, rugged and durable enough in its construction to withstand the severe abuse it will encounter upon its being "shot" through a condenser tube by fluid pressure and at fairly high velocities and then finally stopped abruptly by its sharp impact against an iron condenser or other heat exchanger head after its emergence from the outlet end of the tube.

In addition, the tube cleaner should possess a sufficiently flexible construction in combination with sufficiently resilient scraper blades to enable the tool to adapt itself to any abnormal irregularities within the tube, as encountered by it in its passage therethrough, and still permit the scraping blades of the tool to effectively clean the inside walls of the tube.

According to the present invention there is provided a tube cleaner possessing all the above described desirable properties for use in hydraulic "shot" cleaning of condenser units with tubes of relatively small diameter, ranging down to as small as four-tenths of an inch inside diameter.

However, it is not desired to restrict the scope or method of use of the specific embodiment of the tube cleaner as shown and described herein, but it is appreciated that the tool may advantageously be manufactured and used for cleaning large diameter condenser tubes; and that when the tool is used with either large or small tubes, it may be manually pushed through the tube by a rod, as well as being shot therethrough under fluid pressure.

My invention may be more fully understood by reference to the accompanying drawings, in which:

Fig. 1 is a side elevation of a cleaner embodying my invention.

Fig. 2 is a view similar to Fig. 1 but with the cleaner rotated 90°; and

Figs. 3 to 7 inclusive are perspective views on

2

a larger scale of the several elements of the cleaner.

The cleaner, as illustrated in the drawings, comprises a main body member having a circular head 2 and a flat shank 3. Carried on this body is a resilient scraper element 4. There is a second body element 5 secured to this scraper and this in turn carries a second resilient scraper element 6, to which in turn there is attached another element 7.

The scraper 4 is a generally V-shaped member formed of spring steel or other metal, the scraper having two arms 4a which diverge toward their free ends and the free ends of which are turned outwardly to provide semi-circular scrapers 4b, there being a hole 4c in each arm, as shown. The bend connecting the two arms is designated 4d.

The free end of the shank 3 of the first body member is bifurcated, originally being in the form shown in dotted lines, providing a recess 8 into which the bend or base 4d of the scraper 4 is received, after which the bifurcated ends of the body are bent inwardly to form retaining lugs 9. This provides a method of retaining the scraper element flexibly on the body.

The body element 5 is bifurcated at one end like the body 3, providing an opening 10 and lugs 11 to hold the scraper element 6 which is exactly similar to scraper 4. The other end of the body element 5 has a generally V-shaped notch therein in providing two forwardly extending arms 13, terminating in the lugs 14 that engage in openings 4c of the scraper 4. The member 5 is thus flexibly connected in this manner with the body 3 and is in a plane at right angles to body 3, so that its scraper elements are rotated with respect to the axis of the assembly 90° from the scrapers 4b on the scraper element 4, and the scraper 4 is confined by the arms 13 so that the scraper blades can exert the necessary pressure but the arms 4a cannot spread apart too far.

The part 7 is shaped like the forward end of part 5, it being provided with a V-shaped notch between diverging arms 15 terminating in the lugs 16 to engage the openings 6c in the arms 6a of the scraper 6 and thus confine these arms from opening out too far.

Thus the cleaner is an articulated structure having at least two of the two-bladed scrapers, 50 with the blades of one being angularly rotated

90° from the other. Simple punch press operations may be used for shaping the parts. It may be cheaply constructed, has the necessary resiliency but the scrapers are restrained from opening out too far; it may be made in small diameters and still have the desired qualities of flexibility, and the lugs 9 spaced from the opposite faces of the body 5, and the lugs 14 between which the body 3 extends, limit the relative flexing movement of the parts.

It is understood that the scope of the present invention is not to be limited to the specific embodiment shown and described herein, except as limited by the scope of the following claims.

I claim:

1. A tube cleaner comprising a flat body member having a transverse slot adjacent one end thereof and a substantially V-shaped scraper element constituted of a continuous length of thin, flat metal stock having the base of the V received in said slot whereby the element is restrained from turning transversely on an axis normal to the plane of the flat body by the coacting surfaces of the flat stock and the boundaries of the slot and also restrained against longitudinal movement, while the element as a whole may rock to a limited extent in a direction normal to the plane of the flat body upon pressure being applied to one arm or the other and having the arms thereof extending longitudinally along the body in spaced relation thereto, the free ends of the scraper arms being turned outwardly to form blades which are spaced from the body.

2. In a tube cleaner, a flat body element having a bifurcated end portion with inwardly turned spaced lugs and providing a transverse slot, a substantially V-shaped scraper element confined in the slot and retained therein by the inwardly turned lugs the scraper element being constituted of a continuous length of thin, flat metal stock, the scraper element having arms which extend forwardly along the body and diverge from the flat sides of the body, the free ends of said arms being turned outwardly to provide scraper blades, the crotch of the V being in said slot whereby the scraper element may rock relative to the body in a plane normal to the sides of the flat body element while being restrained by the boundaries of the slot from turning on an axis which is normal to the face of said flat body.

3. In a tube cleaner, a flat body element having a bifurcated end portion with inwardly turned spaced lugs and providing a transverse slot, a substantially V-shaped scraper element confined in the slot and retained therein by the inwardly turned lugs, the scraper element having arms which extend forwardly along the body and diverge from the flat sides of the body, the free ends of said arms being turned outwardly to provide scraper blades, said arms each having an opening therein near the free end thereof, a second body element having an end portion similar to the first one with a similar scraper thereon, the opposite end of said second body member being bifurcated to provide legs which embrace the first scraper element, said legs being provided with lugs that are entered in the openings in the arms of the first scraper element.

4. A tube cleaner comprising a flat body member having a bifurcated end portion with inwardly turned lugs providing a transverse slot in said body, a substantially V-shaped scraper element having the base thereof engaged in said slot and having arms which extend along the sides of the body, the free ends of the arms be-

ing turned outwardly to provide scraper blades, each arm having an opening therein adjacent its free end, a second flat body member at right angles to the first having a bifurcated end portion with inwardly turned lugs at one end thereof, which end portion embraces the said scraper element and the lugs of which are entered in the openings in the arms of said scraper element, the other end of said second body member being constructed similarly to said end of the first body member and having a similar scraper element thereon.

5. A tube cleaner comprising a flat body member having a bifurcated end portion with inwardly turned lugs providing a transverse slot in said body, a substantially V-shaped scraper element having the base thereof engaged in said slot and having arms which extend along the sides of the body, the free ends of the arms being turned outwardly to provide scraper blades, each arm having an opening therein adjacent its free end, a second flat body member at right angles to the first having a bifurcated end portion with inwardly turned lugs at one end thereof, which end portion embraces the said scraper element and the lugs of which are entered in the openings in the arms of said scraper element, the other end of said second body member being constructed similarly to said end of the first body member and having a similar scraper element thereon, and a bifurcated body having arms which embrace the second scraper and having lugs which enter the holes in the arms of the second scraper, which last named body limits the spreading of the arms of the second scraper.

6. A tube cleaner comprising a flat body member having a bifurcated end portion with inwardly turned lugs providing a transverse slot in said body, a substantially V-shaped scraper element having the base thereof engaged in said slot and having arms which extend along the sides of the body, the free ends of the arms being turned outwardly to provide scraper blades, each arm having an opening therein adjacent its free end, a second flat body member at right angles to the first having a bifurcated end portion with inwardly turned lugs at one end thereof, which end portion embraces the said scraper element and the lugs of which are entered in the openings in the arms of said scraper element, the other end of said second body member being constructed similarly to said end of the first body member and having a similar scraper element thereon, the second body element being telescoped between the lugs of the first body element, and the first body element being received between the said lugs on the arms of the second body element whereby relative pivoting movement of said body members is restricted.

7. A condenser tube cleaner comprising a flat body member having a disk-shaped head at one end and having its other end bifurcated and with inwardly turned lugs at said other end, a two-armed scraper entered in the bifurcated portion of said body member and having arms which extend along the body member with outwardly turned blade portions at the free ends thereof, each arm having a hole therein near its outer end, a second flat member in a plane perpendicular to the first and having forwardly extending arms at one end thereof with inwardly turned lugs at the ends thereof, said arms embracing the scraper on the first body member and having the lugs thereof pass through the holes in the arms of said scraper, the other end of the

second body member being bifurcated similarly to the first and having a similar scraper therein, and a third body member having forwardly extending arms with inwardly turned lugs at the ends thereof, which third body member embraces the scraper element on the second body element and the lugs of which pass through the holes in the second scraper element, the last named body member confining the second scraper element against spreading.
